(57) **CLAIM**

The ornamental design for a toothbrush holder, as shown and described.

DESCRIPTION

FIG. 1 is a front perspective view of a toothbrush holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 2; and, FIG. 11 is an enlarged detail view of area 11 in FIG. 2.

The dash-dash broken lines in the drawings illustrate the portions of the toothbrush holder, which form no part of the claimed design.

The dash-dot-dash broken lines encircling the enlarged views depict reference to the enlarged views and form no part of the claimed design.

The claim is directed to the design shown in solid line and shaded surfaces, and does not include any unshaded surfaces that are shown between the broken lines and solid lines, or the circular interior bottom surface.
